(57) **CLAIM**

The ornamental design for an illuminated insect repeller, as shown and described.

DESCRIPTION

FIG. 1 is a perspective view of an illuminated portion of an illuminated insect repeller according to the design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top side elevational view thereof; and,

FIG. 7 is a bottom side elevational view thereof.

The broken lines depicting upper and lower housing components are provided for location reference purposes and form no part of the claimed design.
